TAPE CONDENSER

Lionel Desrosiers, Lachute Mills, Quebec, Canada,
assignor to Davis & Furber Machine Company,
North Andover, Mass., a corporation of
Massachusetts

Application October 20, 1943, Serial No. 507,010

11 Claims. (Cl. 19—151)

This invention relates to tape condensers used in the textile industry for dividing a web of fibers into slivers and condensing the latter into rovings.

In this type of machine the web is fed to dividing mechanism comprising dividing rolls and co-operating tape runs which serve to progressively tear the web into slivers, the tape runs being arranged to carry adjacent slivers along diverging paths from the dividing rolls to condensing aprons which serve to condense the slivers into rovings.

When the web fed to the tape condenser is composed largely of long fibers it frequently happens that complete separation of adjacent diverging slivers is resisted by connecting fibers left extending therebetween by the dividing mechanism. This resistance continues until the connecting fibers break or are torn free from one of the slivers and results in serious difficulties, such as breakage of the slivers and the production of slivers of non-uniform cross section and fiber content.

The purpose of the present invention is to provide an improved fiber severing attachment which will operate efficiently over a long period of time without requiring repair, replacement or adjustment of its component parts. This purpose is achieved by providing a fiber severing attachment comprising (1) a slot-defining structure arranged at the rear of the dividing point or line of divergence of the slivers and defining a plurality of relatively narrow, vertically extending slots positioned to receive therein the central portions of the connecting fibers extending between and resisting separation of adjacent diverging slivers; and (2) a series of relatively spaced, travelling fiber engaging elements arranged to travel across said slots in close proximity to the rear side of the slot-defining structure and to cooperate with side walls of said slots in severing the connecting fibers entering said slots.

In the preferred embodiment of my invention the slot-defining structure comprises a plurality of laterally spaced, vertically disposed fingers depending from a suitable supporting bar, said fingers being bent to present upper and lower curved portions which are respectively positioned close to the upper and lower dividing rolls and are substantially concentric with the cylindrical surfaces of said rolls. The cooperating fiber-engaging elements preferably comprise an endless series of spaced, horizontally disposed, pin-like projections carried by an endless belt trained around a pair of pulleys, one of which is driven from a live shaft of the condenser. The belt is arranged so that the pin-like projections, in moving through

a portion of their endless path of travel, cross said vertically extending slots in close proximity to the rear side of the slot-defining fingers. The fibers entering said slots are thus engaged by said pin-like projections and move against the sides of the slots toward which the pin-like projections are travelling with the result that said fibers are severed in a satisfactory manner without damaging the slivers between which the fibers extend.

10 Proceeding now to a more detailed description of this invention reference will be had to the accompanying drawings, in which—

Fig. 1 is a rear elevational view showing the application of my invention to the dividing mechanism of a conventional tape condenser. In this view the tape runs have been omitted and the dividing rolls have been shown as plain rolls since the showing of the tape runs and the grooved formation of the dividing rolls would interfere with a clear showing of the component parts of said invention.

Fig. 2 is a sectional view taken substantially along the line 2—2 of Fig. 1.

Fig. 3 is a top plan view of the assembly shown in Fig. 1.

Fig. 4 is an enlarged detail view of a belt guiding and supporting element forming part of the assembly shown in the preceding figures.

Fig. 5 is an enlarged detail view, partly in side elevation and partly in vertical section, of a belt driving pulley arrangement and pulley supporting bracket forming part of the assembly shown in the preceding figures.

In the present drawings I have shown only those parts of a conventional tape condenser which are necessary to an understanding of my invention. Such parts comprise the frame members 5, the dividing rolls 6, the tape runs 7, and two shaft elements 8 and 9 which are utilized to drive component parts of my improved fiber severing attachment. The tape runs 7 cooperate, in a well known manner, with the dividing rolls 6 to divide the fibrous web 10 into slivers 11 and serve to carry adjacent slivers rearwardly along diverging paths from the dividing rolls to upper and lower tape condenser units (not shown).

The slot-defining structure of my improved fiber severing attachment comprises a plurality of laterally spaced, vertically disposed fingers 12 depending from a supporting bar 13 which extends between the frame members 5 and is supported therefrom by suitable brackets 14. The bar 13 is located rearwardly of and relatively close to the upper portion of the upper dividing roll 6. The fingers 12 define a plurality of slots

15 which are properly positioned with reference to the tape runs 7 to receive therein the connecting fibers 16 which are sometimes left extending between adjacent slivers 11 as the latter are carried rearwardly from their point of separation by the tape runs 7. Each finger 12 is bent to provide an upper curved portion 17 merging, at its lower end, with the upper extremity of a similarly curved lower portion 18. The upper curved portion 17 of each finger is positioned close to 10 and substantially concentric with the upper dividing roll 6 and the lower portion 18 is similarly positioned with reference to the lower dividing roll 6. This curvature of the fingers 12 ensures that the connecting fibers 16 will be received in the slots 15 at a point close to the point of separation of the adjacent slivers between which the fibers 16 extend.

The fiber-engaging elements which cooperate with the slot-defining fingers 12 to sever the connecting fibers 16 as the latter enter the slots 15 are here shown as comprising an endless series of spaced, horizontally disposed pin-like members 19 projecting from the outer side of an endless carrier belt 20 which is trained around pulleys 21 and 22 mounted to turn about vertical axes by suitable pulley shafts 23 and 24.

In the present instance belt 20 is shown as a two-ply belt comprising a relatively wide inner ply 25 and a relatively narrow outer ply 26. The pin-like projections 19 are here shown in the form of nails which are passed outwardly through the belt ply 26 so that the heads of the nails lie between this ply and the inner ply 25.

The shafts 23 and 24 about which the pulleys 21 and 22 revolve are carried, respectively, by brackets 27 and 28 fastened to the opposite frame members 5 so that one run of the belt 20 is positioned opposite and relatively close to the portions of the fingers 12 which lie opposite the nip of the dividing rolls 6. In this connection it is important that the positioning of belt 20 with reference to fingers 12 be such that, in moving through a portion of their endless path of travel, the pin-like projections 19 pass across the slots 15 in close proximity to the central portions of the fingers 12 which lie opposite the nip of the dividing rolls 6. This ensures that the pin-like projections 19 will engage the connecting fibers 16 immediately after said fibers are advanced into the slots 15 by the rearward travelling movement of the adjacent diverging slivers between which they extend. The fibers engaged by the projections 19 are forced against side walls of the slots 15 toward which the fiber-engaging projections are travelling and are quickly severed without damaging the adjacent slivers between which said fibers extend.

The pulley 22 has attached thereto a driving pulley 30 which is driven by a belt 31 from a pulley 32 on the previously mentioned shaft 8 which may be any suitable live shaft of the condenser operating mechanism. Since the shaft 8 is located outside the adjacent frame member 5 and rearwardly of the driving pulley 30 the two runs of the driving belt 31 are trained around guide pulleys 35 which are mounted on shafts carried by a suitable bracket 36. A rotary brush 37 is arranged adjacent the rear run of the belt 20 to engage and remove fibers or portions of fibers from the pin-like projections 19 as the latter pass around the pulley 22. This brush is carried by a shaft 38 which extends outwardly through the right hand frame member 5 and is journalled in a suitable bearing bracket 39, the

outer end of said shaft being provided with a pulley 40 which is driven by a driving rope 41 from a pulley 42 mounted on the shaft 9.

Suitable means are provided for supporting and guiding the two runs of the belt 20 at a point intermediate the pulleys 21 and 22 around which the belt is trained. Such means comprises a guide block 45 which is provided, in its upper surface, with front and rear grooves 46 in which the lower edges of the front and rear runs of the belt 20 are supported and guided. This block is fastened to a metal plate 47 which is rigidly secured to a supporting rod 48 extending between and carried by the pulley supporting brackets 27 and 28.

Having thus described the preferred embodiment of my invention it will be understood that various modifications may be resorted to within the scope and spirit of the appended claims. For example, the slot-defining structure may comprise a single appropriately shaped metal plate in which the slots 15 are provided and the fingers 12 may be reciprocated instead of being caused to travel in an endless path.

I claim:

1. The combination with a machine having means for progressively dividing a web of fibers into slivers and directing adjacent slivers along diverging paths of travel, of a slot defining structure located adjacent said dividing and directing means and presenting a plurality of slots extending parallel with the paths of travel of said slivers and adjacent their line of divergence so that connecting fibers left extending between adjacent slivers will be advanced into said slots as the slivers diverge, and means cooperating with said slot defining structure to sever the connecting fibers entering said slots.

2. The combination as set forth in claim 1, in which the last mentioned means comprises a series of fiber engaging elements mounted for travelling movement and means for moving said elements across said slots in close proximity to said slot-defining structure to cooperate therewith in severing the connecting fibers entering said slots.

3. The combination with a machine having means for progressively dividing a web of fibers into slivers and directing adjacent slivers along diverging paths of travel, of a slot defining structure comprising a series of laterally spaced fingers presenting a plurality of slots extending parallel with the paths of travel of said slivers and adjacent their line of divergence to receive therein connecting fibers left extending between adjacent diverging slivers, and means cooperating with said slot defining structure to sever the connecting fibers entering said slots.

4. The combination with a machine having means for progressively dividing a web of fibers into slivers and directing adjacent slivers along diverging paths of travel, of a slot defining structure comprising a supporting bar and a plurality of laterally spaced slot defining fingers carried by said bar and disposed in substantially parallel relation with each other presenting a plurality of slots extending parallel with the paths of travel of said slivers and adjacent their line of divergence to receive therein connecting fibers left extending between adjacent diverging slivers, and means cooperating with said slot defining structure to sever the connecting fibers entering said slots.

5. The combination with a machine having means for progressively dividing a web of fibers into slivers and directing adjacent slivers along

diverging paths of travel, of a slot defining structure presenting a plurality of slots extending parallel with the paths of travel of said slivers and adjacent their line of divergence to receive therein connecting fibers left extending between adjacent diverging slivers, and means cooperating with said slot defining structure to sever the connecting fibers entering said slots, said cooperating means comprising a pair of pulleys mounted adjacent opposite ends of said slot-defining structure and relatively close thereto, an endless belt trained around said pulleys and a plurality of fiber engaging elements projecting from said belt and adapted, during travelling movement of the belt, to travel across said slots in close proximity to said slot-defining structure and means for imparting travelling movement to said belt.

6. The combination with a tape condenser web dividing mechanism comprising dividing rolls and tape runs cooperating with said rolls progressively to divide a web of fibers into slivers and to direct adjacent slivers along diverging paths of travel, of a slot-defining structure located adjacent said dividing rolls and defining a plurality of slots so positioned with reference to said rolls and tape runs that connecting fibers left extending between adjacent slivers will be advanced into said slots as the slivers diverge from the dividing rolls and means cooperating with said slot-defining structure to sever the connecting fibers entering said slots, said means comprising travelling fiber-engaging elements arranged to travel across said slots in close proximity to said slot-defining structure.

7. The combination with a machine having means for progressively dividing a web of fibers into slivers and directing adjacent slivers along diverging paths of travel, of means for severing connecting fibers left extending between adjacent slivers comprising a series of spaced fiber-engaging elements positioned to receive the connecting fibers therebetween, means for moving said fiber-engaging elements transversely of said connecting fibers, and means engaging said connecting fibers to oppose movement thereof by said elements and cooperating therewith to effect the rupture of said connecting fibers.

8. The combination with a machine having

means for dividing a web of fibers into slivers and directing adjacent slivers along diverging paths of travel, of means for severing connecting fibers left extending between adjacent diverging slivers comprising an endless belt, fiber-engaging elements projecting from said belt and adapted to engage said connecting fibers and means for supporting and imparting travelling movement to said belt whereby said fiber-engaging elements are caused to travel in the transverse direction of said fibers.

9. The combination with a tape condenser web dividing mechanism comprising upper and lower dividing rolls and tape runs cooperating with said rolls to divide a web of fibers into slivers and to direct adjacent slivers along diverging paths of travel, of means for severing the connecting fibers left extending between adjacent slivers, said means comprising a slot-defining structure defining a plurality of vertically extending slots positioned to receive therein connecting fibers left extending between adjacent diverging slivers, a pair of pulleys mounted at opposite ends of said slot-defining structure, an endless travelling belt trained around said pulley so that one flight of the belt travels across said slots in close proximity to said slot-defining structure and an endless series of horizontal fiber-engaging projections extending outwardly from said belt and means for imparting travelling movement to said belt.

10. The combination set forth in claim 9, in which said slot-defining structure comprises a supporting bar located opposite the upper portion of the upper roll of the dividing mechanism and a plurality of slot-defining fingers depending from said bar.

11. The combination set forth in claim 9, in which the slot-defining structure comprises a supporting bar located relatively close to and parallel with the upper portion of the upper dividing roll and a plurality of laterally spaced slot-defining fingers depending from said bar, each finger being bent to present upper and lower curved portions which are respectively positioned close to the upper and lower dividing rolls and are substantially concentric with the cylindrical surfaces of said rolls.

LIONEL DESROSIERS.
